The ornamental design for a packaging having a sliding lid, as shown and described.

DESCRIPTION

FIG. 1 is a perspective view of packaging having a sliding lid showing my new design;

FIG. 2 is a top plan view thereof;

FIG. 3 is a top perspective view thereof, with the lid shown in an open position;

FIG. 4 is a bottom plan view of FIG. 1;

FIG. 5 is a front edge elevation of FIG. 1, the undisclosed opposite side being identical;

FIG. 6 is a left side edge elevation of FIG. 1;

FIG. 7 is a right side edge elevation of FIG. 1; and, FIG. 8 is a right side edge elevation of FIG. 3.

FIG. 1

FIG. 2

FIG. 3

FIG. 4

FIG. 5

FIG. 6

FIG. 7

FIG. 8
